UNITED STATES PATENT OFFICE

167,923

DECK OF PLAYING CARDS

Alfred V. Bigley, Albany, N. Y.

Application December 28, 1951, Serial No. 17,851

Term of patent 14 years

(Cl. D34—13)

To all whom it may concern:

Be it known that I, Alfred V. Bigley, a citizen of the United States, residing at Albany, county of Albany and State of New York, have invented a new, original, and ornamental Design for a Deck of Playing Cards, of which the following is a specification, reference being had to the accompanying drawing, forming a part hereof in which

Fig. 1 is a face view of one of the cards of which there are forty in the deck;

Fig. 2 is a face view of another card of which there are four in the deck;

Fig. 3 is a face view of another card of which there is only one in the deck; and

Fig. 4 is a face view of another card of which there are fifteen in the deck, all four figures showing my new design.

The backs of the cards, which are the reverse of those shown, may be plain or printed in any conventional card back design.

I claim:

The ornamental design for a deck of playing cards, as shown and described.

ALFRED V. BIGLEY.
